W. F. TROAST

SLIDING SHACKLE LOCK

Filed Sept. 10, 1924

Inventor:
William F. Troast,

By Wm. F. Babcock & Son

Atty's.

UNITED STATES PATENT OFFICE.

WILLIAM F. TROAST, OF LANCASTER, PENNSYLVANIA, ASSIGNOR TO ISSACHAR F. REESE, OF LANCASTER, PENNSYLVANIA.

SLIDING-SHACKLE LOCK.

Application filed September 10, 1924. Serial No. 736,924.

This invention relates to locks, and more particularly to sliding shackle locks for general use, including also use on automobile tire carrier clamps to prevent tires from being stolen or, in other words, to locks of the general sliding or adjustable shackle type shown in the patent to Benson, No. 1,223,928, granted April 24, 1917, in which the lock-casing or block has openings extending from top to bottom or front to rear completely through the casing or block to adjustably receive the parallel arms of the substantially U-shape shackle, which arms may extend beyond each end of the casing and are adapted to be engaged by the lock mechanism extending in said openings or passageways in the path of travel of said arms respectively.

The invention resides more particularly in the locking mechanism and in the combination and interrelation thereof with the casing and shackle, and also in details of the casing or block and in details of the shackle construction.

The primary objects in view are to provide a very cheap reliable positive locking means; to provide a construction wherein the locking element or mechanism may be slipped on the arms of the shackle and the latter together with said locking mechanism correctly positioned in one plate of the casing or block and the other plate of the casing then applied and the whole riveted together, holding all parts permanently in correct position and relation, thus greatly reducing the labor and time heretofore required in assembling such locks; to provide such a combination of the shackle and locking element that the former, if inserted from the correct end or direction, will be positively engaged by the locking element and positively held thereby until released by the movement of said locking means or element by the key to inoperative position, but, if inserted from the wrong end or direction will be yieldingly engaged by said locking element, but will not be positively held by said locking element, and may be pulled easily out of the casing or block without any need to use the key, whereby all need for guard stop means for preventing insertion from the wrong end of the casing or wrong direction is eliminated; to provide a spring lock mechanism which may be held by the key in inoperative position when the key has

been turned to a definite position and will not act to turn the key from such definite position when the key is released by the operator; and to provide a shackle having its loop or closed end provided with opposed faces extending from the ends of the parallel arms and converging toward each other with straight walls at an angle of approximately sixty degrees to obtain the quickest centering angle and the closest possible adjustment to hasp or fastener over a relatively large range so as to prevent rattling and, of more importance, to make such a tight fit that the movable lug I can not be twisted, turned or rocked to such a position as to permit the removal of the spare tire even though the bolt J be removed, and so that the body or casing of the lock will so tightly engage the lug I as to prevent the insertion between the arms M of said shackle and the body or casing of said lock and the lug I of a prying instrument, all of which objects, among others, are accomplished by the combination, construction and arrangement of parts all as hereinafter more particularly set forth, described and claimed.

In the accompanying drawing, in which only two embodiments of my invention are shown merely by way of illustration of instances of the practice of my invention to aid in its better understanding, but with no intention of being limited to the details thereof, it being recognized that it is capable of numerous other embodiments:

Figure 1 represents a vertical cross-sectional view through a portion of a spare tire rack of ordinary construction in common use on automobiles, illustrating the application of a lock, according to one embodiment of my invention, to the securing lugs by which a mounted tire or casing is fastened to the rear of a vehicle, a part of one of the plates of the lock casing or body being broken away to better show the locking mechanism and the combination and interrelation of parts;

Figure 2, a sectional view on the line 2—2 of Fig. 1, the sides of the key-guide and support K being omitted in the interests of clarity.

Figure 3, a view similar to Fig. 2, only illustrating the locking element as spread to inoperative position and held so by the key;

Figure 4, a sectional view on the line 4—4 of Fig. 1, looking in the direction of the arrow;

Figure 5, a detail side elevation of the 5 spring locking element;

Figure 6, a detail end elevation of the spring locking element;

Figure 7, a detail rear or bottom elevation of the spring locking element;

10 Figure 8, a detail sectional view on the line 8—8 of Fig. 1;

Figure 9, a view, similar to Fig. 2, of a modified form; and

15 Figure 10, a sectional view on the line 10—10 of Fig. 9, looking in the direction of the arrow.

Referring now in detail to the drawings, the lock block, casing or body comprises two plates A and B preferably riveted together by means of rivets C preferably integral with one of the plates, plate A for instance.

Each plate is provided on its inner face adjacent its bottom or rear end with a key supporting rib D in line with the key-hole 25 disc or washer E and the angular key-guide and support K, the rib D and key-guide and support K on the plate A registering with the corresponding rib D and key-guide and support K on the plate B, the adjacent opposed edges of the ribs D and the top and bottom or front and rear h and h' of the key-guides and supports K being formed to permit the insertion of the key L therebetween and to act as bearings and supports 35 for said key L during the turning movement of the latter when spreading the sides 2 of the locking element or mechanism.

In the embodiments shown the rivets C are integral with the plate A, four in number, and located one at each end of the rib D of said plate A and one on each side of the key-guide and support K and near the top or front end of the said plate A, and the plate B is provided with a corresponding number of cooperating perforations 45 respectively receiving said rivets C in assembling.

Said plates each have their top and bottom or front and rear ends cut out, as usual, 50 on each side beyond said rivets and perforations respectively and are provided between said walls with arcuate supporting ribs, which walls and ribs of the one plate, in the assembling of the plates, register with the corresponding walls and ribs of the other plate to define passageways or openings 55 completely through the lock block or casing for the reception of the arms M of the shackle as usual in this type of lock. Adjacent the top or front of the lock plates and on the distant faces thereof, each plate is provided with a long wide web 1 flush with the edge of the opening or cut-out 60 therein so that the webs 1 of the respective plates A and B in assembled relation will

register with each other and constitute bearing faces preventing canting of the shackle during the initial stage of insertion of the end portions of the arms M thereof.

The ribs D, key-guides and supports K, 70 rivets C and webs 1 will preferably be integral with their respective plates as shown.

The locking mechanism consists of a single element, a long, wide, approximately V-shape sheet metal leaf spring, which has 75 two side members 2 converging from front to rear or top to bottom and having its lower or rear edges free and normally held toward each other by the form and resiliency 80 of said spring element as a whole, and have their upper or front and most widely separated portions connected together by the integral web 3, which web has each end 85 arcuately cut out, as at 4, to receive the respective opposed smooth inner faces of the 90 arms M of the shackle, and has a central perforation 5 to receive and act as a bearing for the reduced end of the key L.

The sides 2 are each provided with an angular opening 6 extending from a point 90 near the bottom or rear edge thereof to the top web 3, the openings 6 in the two sides 2 registering and being so located and of such size and shape as to snugly receive the 95 key-guides and supports K of the respective plates, which key-guides and supports K maintain said spring element in correct operative position. Also, the four rivets C will aid, in the embodiments illustrated, in such positioning of the spring element, the 100 web 3 of which corresponds in width substantially to the internal thickness of the 105 lock block or casing at such point.

The shackle is comprised of two long parallel arms M, each having notches 7 on both side faces and in registry, and having smooth opposed inner faces and smooth outer faces, the notches being formed with inclined sides and abrupt ends to be engaged by the edges of the respective sides 2 of the 110 spring element, the sides of the notches being preferably formed on angles corresponding in degree to the inclination of said sides 2 of the spring element.

The parallel arms M of the shackle are of 115 equal length and each extends from its free end to a point near the loop end of the shackle, starting at which point a straight portion 8 inclined at approximately 60 degrees extends for a considerable distance, 120 relatively speaking, toward the other arm M, the portions 8 having their extreme and closer ends connected together by a short arcuate end portion 9, the inclined portions 8 and the end portion 9 together forming a 125 sharp angle loop with long flattened side portions, and being integral with the arms M, all as well illustrated in Figure 1.

It will be seen that as thus described and illustrated, the lock consists of but five dis-

tinct parts, the two plates A and B, the key-hole disc or washer E, the spring element, and the shackle, thus making for the greatest simplicity and economy of material and 5 greatly simplifying the assembly operations, whereby great economy of time and labor in assembling is obtained. Also, it is to be noted that, while the key-hole disc or washer E is desirable, it is not essential.

10 To assemble, the spring element will be slipped along the arms M from their free ends toward the end portion 9 with the web 3 nearer the latter, to a position such as 15 illustrated in Figure 1. The spring element as thus applied to the arms M of the shackle will then be positioned in the plate A, key-hole disc or washer E fitted in place, the plate B fitted in place, and then the ends 20 of the rivets C will be spread and the assembly operation will be complete.

From the above description taken with the illustration of the drawing it will be obvious that the shackle may easily be improperly inserted from the bottom, but it is also very 25 obvious that if said shackle should be inserted from the bottom or rear there would be no abrupt faces of the notches 7 that could be engaged by the lower or rear edges of the sides 2 to prevent endwise withdrawal 30 of said arms.

Also, from Fig. 3, it will be seen that when the arms M have been properly inserted from the top or front and are locked by the sides 2 of the spring element, they 35 may be released by the insertion and operation of the key L, which is adapted to engage the lower or rear portions of said sides 2 and spread them apart so that they will lie out of the paths of said notches, and if said 40 key L be turned to, and left at, a position at right angles to its insertion position it will serve as a block holding said sides 2 spread to inoperative position, permitting the easy and quick unimpeded removal and insertion 45 of the shackle with one hand.

In the modification illustrated in Figures 9 and 10, in place of the single spring element, two springs 2^a, each conforming in size, inclination, shape and arrangement to 50 said sides 2, are substituted, being preferably held in place to the respective plates A and B by rivets 2^b preferably integral with the respective plates. Otherwise the construction, operation and combination of 55 parts are in all respects the same as that of the embodiment illustrated in Figures 1 to 8.

The letter F designates the skeleton rim forming part of, and supported by, the usual iron tire rack, not shown, with which 60 most automobiles are provided for carrying spare tires. A demountable rim G adapted to have mounted on it a pneumatic tire or spare casing, is loosely fitted over the rim F. A metal lug H, welded, riveted, or both, 65 to the rim F, is provided with a notch or re-

cess in its upper end, a perforation intermediate its ends, and a bolt hole near its lower end, and an opposing removable lug I, of usual type, having its lower portion downwardly inclined away from lug H and provided with a perforation and bolt hole registering with the perforation and bolt hole in lug H and having a registering notch or recess in its upper end, is normally tensionally held by a bolt J and its nut with its adjacent face of its inclined portion in engagement with the demountable rim G, forcing the latter over on rim F and also spreading the rim G radially, to secure the rims F and G together and prevent any substantial relative movement between these rims. 70

To surely lock the removable lug I to the lug H to prevent rattle and to prevent the unauthorized removal of the rim G with the spare tire mounted thereon, it is essential to 85 provide a lock that can be so adjusted that the lock block or body will lie so closely to the adjacent face of the lug I as to prevent the insertion of a prying instrument between said lug I and the lock block or body to pry 90 it off, and which will lie so closely to said lug I and will bind said lug I and lug H so tightly as to prevent the lug I from being twisted or rocked in any direction relative to lug H to such degree as would, even 95 should the bolt J be removed, permit the spare rim G to be removed with its spare tire, and it is to accomplish this end that the shackle is provided with the converging faces 8 inclined at an angle of approximately 100 60 degrees, as illustrated in Fig. 1.

In use the shackle will be applied to the lugs H and I with the arms M extending in the registering recesses and the registering perforations thereof and with the free ends 105 of said arms presented rearwardly; the lock block or casing is then applied to the free ends of said arms and forced along the same until it is in tight engagement with the adjacent face of lug I with the opposing faces 110 of lugs H and I parallel, to, and in full engagement with, each other, and the opposed faces of inclined portions 8 in biting engagement with the walls of the recess and perforation respectively in lug H, thus guarding against any play between the lock and said lugs thus preventing any rattling or noise, and guarding against any forced movement of the lug I, in any direction with relation to lug H, of sufficient extent as 115 to render said lug I inoperative to hold the rim G on rim F even though the usual bolt J be removed in an attempt at unauthorized removal of the spare tire and rim.

Having thus described my invention, what 125 I claim as new and desire to secure by Letters Patent is:

1. In a sliding shackle lock, the combination of a sliding shackle with a lock-casing, said lock-casing comprising sections having 130

- integral parts together, as assembled, constituting a key-guide and support, and a substantially V-shape spring locking means having leaves converging toward each other from front to rear and having the material of said leaves cut out to snugly receive said key-guide and support during the assembly operation, the said spring locking means being held in correct position solely by said key-guide and support, and the said shackle being provided on both sides of its legs with notches presenting abrupt faces to be engaged by the opposed faces of said spring locking means.
15. 2. In a sliding shackle lock, a shackle having two parallel arm portions having free ends, one of said arms having a straight inclined portion extending from its other end

portion at an abrupt angle for a considerable distance toward the other arm portion ²⁰ and away from the free end portions of said arms, said inclined portion being integrally connected with the other arm portion.

3. In a sliding shackle lock, a shackle having two parallel arm portions having free ends, each of said arm portions having a straight inclined portion extending from its other end at an abrupt angle for a considerable distance toward the other arm portion, and the adjacent extreme parts of said inclined portions being integrally connected. ²⁵

In testimony whereof, I have signed my name to this specification at Lancaster Pennsylvania this 5th day of September 1924.

WILLIAM F. TROAST.
